SELF-PROPELLED HYDRAULIC HAMMER

Evan E. Dorkins, Ottawa, Kans., assignor to
 Ottawa Steel Products, Inc., Ottawa, Kans., a
 corporation of Kansas

Application August 23, 1950, Serial No. 181,069

7 Claims. (Cl. 262—13)

1

This invention relates to drop hammers and carriages or vehicles therefor and more particularly to a drop hammer on a carriage or vehicle adapted to be self-propelled or otherwise moved to places of use for driving and/or pulling objects and performing work such as breaking, cutting or otherwise hammering and/or tamping pavement, soil and the like, and moving the vehicle and/or hammer mounting during such work in selected directions to progressively work larger areas, said invention being an improvement of that disclosed in my co-pending application, Serial No. 138,811, filed January 16, 1950.

The objects of the invention are to provide a self-contained, portable unit including a carriage or vehicle including a power-driven hydraulic system and an hydraulically operated drop hammer mechanism adjustably and movably mounted on the carriage or vehicle for vertical operation of the hammer when the carriage is on uneven or sloping surfaces and swinging movement laterally of the vehicle for hammering or otherwise working a path of wide width relative to the vehicle; to provide a portable drop hammer mechanism on a carriage or vehicle adapted to perform a large variety of functions both when stationary and when moved over a surface as in road or right-of-way repair and maintenance; to provide an hydraulically operated drop hammer mechanism mounted on a suitable carriage or vehicle in such a manner as to be tilted in any direction from a relatively vertical position and operated in said tilted position; to provide hydraulic means for raising an impact member or hammer as desired to the upper limit of its motion and dropping the same by release of the hydraulic fluid; to provide mechanism having control of a drop hammer at all times to permit substantially free falling of the hammer; to provide a drop hammer trackway mounting adapted for folding said trackway relative to a carriage for travel to locations of work; to provide for controlling operation of the drop hammer from the driving seat of the vehicle whereby the operator has full control of the hammer, hammer operating mechanism, lateral movement of the hammer mechanism, and forward and reverse movement of the vehicle for easily maneuvering, placing in position and operating the entire structure without assistance from others; to provide a mounting for the hammer mechanism for swinging same laterally of the vehicle selectively on a line parallel with the front axle or in an arc

2

about a pivotal connection between the mounting and vehicle; to provide an hydraulic motor and hydraulic controls for raising the impact member or hammer and dropping same; and to provide apparatus of this character that is economical to manufacture, sturdy in construction, versatile, and efficient in operation to give either fast or slow, and light or hard smashing blows with substantially no shock to the apparatus or operator.

In accomplishing these and other objects of the present invention, I have provided improved details of structure, the preferred forms of which are illustrated in the accompanying drawings, wherein:

Fig. 1 is a side elevation of a self-propelled vehicle with a hammer trackway in folded condition for travel to locations of work, portions being broken away to better illustrate the structure.

Fig. 2 is a longitudinal sectional view through the hammer and vehicle therefor, with the trackway for the hammer in upright position for operation of the apparatus.

Fig. 3 is a plan view of the vehicle, the hammer and trackway thereon being shown swung laterally from the longitudinal center of the vehicle.

Fig. 4 is a partial perspective view illustrating the hammer trackway mounting and lateral movement mechanism.

Fig. 5 is a transverse sectional view through the trackway mounting on the line 5—5, Fig. 2.

Fig. 6 is a detail perspective view of the hydraulic operated mechanism on the upper end of the trackway for raising the hammer and dropping same.

Fig. 7 is a diagrammatic view of the hydraulic circuits and mechanism for operating the hammer and mounting.

Fig. 8 is a detail perspective view of a modified form of hammer raising mechanism.

Fig. 9 is a diagrammatic view of the hydraulic circuits and modified mechanism for raising the hammer and dropping same.

Referring more in detail to the drawings:

1 designates a multi-purpose drop hammer mechanism and vehicle or carriage embodying the features of the invention, adapted to be self-propelled or otherwise moved to locations where work is to be done and also for movement during actual operation of the hammer. The vehicle or carriage 2 includes a frame 3 having spaced members 4 and 5 longitudinally of and converging forwardly of the vehicle. The frame

members 4 and 5 are rigidly connected by a suitable number of spaced, transverse members, for example the members 6, 7 and 8, to form a rigid, strong frame structure. Brackets 9 are fixed to the frame members 4 and 5 adjacent the rear ends thereof, and depend therefrom and are suitably and rigidly fixed to an axle 10 which includes differential gearing enclosed in a housing 11 and having driving connection with rear wheels 12 carried by the axle 10.

The transverse member 6 at the forward end of the frame members 3 and 4 is provided with spaced depending flanges 13 and 14 having aligned bores 15 for suitably mounting a pin 16 arranged on the longitudinal center of the vehicle. A bearing 17 is rotatably mounted on the pin 16 and fixed to the front axle 18 whereby said axle will rock about the pin 16 or an axis longitudinally of the vehicle. The axle 18 is preferably a structural shape such as an I or H-beam with a web 19 in a vertical plane and the upper and lower flanges 20 and 21 respectively extending forwardly and rearwardly of the web relative to the vehicle. The axle 18 is preferably substantially longer than the rear axle 10 and has sleeves 22 fixed on the ends thereof. Kingpins 23 are rotatably mounted in the sleeves 22 preferably on a substantially vertical axis and are provided with outwardly turned arms 24 on which front wheels 25 are suitably mounted for rotation, the spacing between the front wheels preferably being considerably greater than the spacing between the rear wheels 12 for a purpose later described. Fixed to the kingpins 23 are arms 26, having free ends suitably connected by links 27 to an arm 28 operatively connected to a steering gear located in a housing 29 for operation by a steering wheel 30 located in a suitable position for turning by an operator sitting in a seat 31 suitably mounted on a plate 32 or other structure carried by the frame members and forming a floor thereon for supporting the operator-driver, intermediate the ends of the frame 3. This arrangement provides the operator-driver with a view forwardly of the vehicle and permits center point steering of the front wheels 25. Also the wheels 12 and 25 may be equipped with brakes selectively and/or individually operated by foot pedals 33, suitably located for the convenience of the operator-driver. The operating structure of the brakes, being conventional, is not illustrated.

An engine or other prime mover 34 is mounted on the frame 3 and is operatively connected with an hydraulic pump 35 and also through a clutch 36 and gear shift type transmission 37 to the differential gearing in the housing 11 for suitably moving the vehicle forwardly and rearwardly. In the particular structure illustrated, the drive shaft 38 is provided with a gear 39 having meshing engagement with a gear 40 fixed on a countershaft 41 rotatably mounted in spaced bearings 42 suitably supported on the plate 32. Sheave pulleys 43 are fixed on the countershaft 41 and are drivingly connected by belts 44 with sheave pulleys 45 which drive the pump 35. The countershaft 41 is also provided with sheave pulleys 46 drivingly connected by belts 47 with sheave pulleys 48 rotatably mounted on a countershaft 49 which is also rotatably mounted in spaced bearings 50 carried on the plate 32.

The clutch 36 is mounted on the countershaft 41 for drivingly connecting the sheave pulleys 48 therewith, said clutch being operated by a foot pedal 51. A sprocket 52 is fixed to the countershaft 49 and is drivingly connected by a suitable

chain 53 with a sprocket 54 fixed on the drive shaft 55 of the transmission 37, the driven shaft of said transmission being connected by a universal joint 56 with the drive shaft of the differential gearing in the rear axle housing.

The transmission 37 is preferably suitably mounted on the frame 3, substantially in alignment with the drive shaft of the differential, and is provided with a gear shift lever 57 which extends upwardly and forwardly adjacent the seat 31 for the convenience of the operator-driver in shifting gears for forward and reverse movement of the vehicle and providing various speeds therefor.

A bracket 58 preferably fixed to the transverse member 7 depends from the frame 3 and is preferably provided with a bearing 59 in which is rotatably mounted the forward end of the transmission drive shaft 55. The bracket 58 is also preferably connected by a ball and socket joint 60 with the rear ends of radius rods 61 which diverge forwardly and have their forward ends suitably connected adjacent the ends of the front axle 18 for additional support of same. A sleeve 62 is preferably fixed to the transverse member 7 and bracket 58, with its bore 63 coaxially of the pin 16 for slidably mounting a ball 64 having a shank extending downwardly through a slot 65 in the sleeve 62, which shank is fixed to the rear end of a horizontally arranged A-frame 66.

The A-frame 66 preferably consists of an angle bracket 67 to which the shank of the ball 64 is secured. The angle bracket 67 is rigidly fixed to the rear ends of spaced forwardly diverging members 69 which extend under and in engagement with the bottom surface of the flange 21 of the front axle 18. The A-frame members 69 extend forwardly of the front axle and have their ends connected by vertically spaced plates 70 and 71, said plates being fixed in engagement with the upper and lower surfaces respectively of the frame members 69. The A-frame members 69 are also connected by a transverse plate 72 arranged substantially under the front axle and supporting a sleeve 73, having a bore 74 extending vertically therethrough. A yoke 75 is supported on the sleeve 73 and rotatably connected therewith by means of a headed bolt 76 extending through an aperture in the yoke and through the bore 74. Screwed on the end of the shank of the bolt is a castellated nut 77 with an antifriction thrust bearing 78 between the nut 77 and the lower end of the sleeve 73. It is preferable that a plurality of washers 79 be arranged between the yoke and sleeve for adjusting the relative positions thereof as later described.

The yoke is provided with legs 80 which extend upwardly and straddle the front axle 18. Fixed to each of the legs 80 are laterally extending arms 81 which extend beyond the A-frame members 69 and rotatably mount rollers 82 adjacent the ends thereof. The rollers 82 are preferably of the flange type and adapted to rollingly engage the upper surface of the lower flange 21 of the front axle, said rollers supporting the weight of the A-frame and mechanism carried thereby, and by adjusting the bolt and nut 76 and 77 and removal or addition of washers 79, a sliding contact between the A-frame members 69 and the bottom of the front axle is adjusted to provide proper support as well as swinging movement of the A-frame laterally of the vehicle, the movement of said A-frame being determined by the rollers 82 on the yoke 75 and its connection through the sleeve 73 with said A-frame

and the ball 64 and sleeve 62, the ball moving longitudinally of the vehicle in the bore 63 of the sleeve 62 as the A-frame is moved laterally of said vehicle.

The lateral movement of the A-frame 66 is effected by means of an hydraulic cylinder and piston mechanism 83, one end 84 of which is pivotally mounted on a bracket 85 which is secured to the front axle 18 with the other end, for example the end of the piston rod, being pivotally secured to a bracket 86 fixed on an A-frame member 69. The hydraulic cylinder and piston mechanism 83 preferably is of the double-acting type whereby application of hydraulic pressure to said cylinder and piston mechanism, as later described, will actuate same to effect expansion or contraction and desired movement of the A-frame 66 relative to the front axle 18.

A vertical shaft 87 extends through suitable apertures in the plates 70 and 71 and is secured thereto as by welding, said shaft extending upwardly from adjacent the forward end of the A-frame 66 and rotatably mounting a column 88. The column 88 is preferably polygonal in cross-section and is hollow, having spaced bearings 89 and 90 fixed therein and rotatably engaging the shaft 87. The column also preferably has a plate 91 fixed therein adapted to rest on an antifriction thrust bearing 92 mounted on the upper end of the shaft 87 for supporting said column and mechanism carried thereby, with the lower end of said column spaced slightly from the upper surface of the plate 70. The column is provided with an ear 93 projecting therefrom and adapted to be secured by means of a bolt or the like to a bracket 94 on the forward end of the A-frame to prevent relative rotation between the column and A-frame, however, the ear 93 is adapted to be pivotally connected to one end of a link 95, the other end of which is pivotally connected to a bracket 96 fixed on one of the arms 81 whereby the column is rotated relative to the A-frame during lateral movement thereof to maintain a parallel relationship between the column and front axle 18 of the vehicle. The column 88 has a suitable bore 97 extending therethrough longitudinally of the vehicle for rotatably mounting a shank 98 of a suitable yoke 99, said yoke having a shoulder 100 engaging the forward side of the column for cooperation with a collar 101 secured to the end of the shank and substantially engaging the rear face of the column to eliminate endwise motion of the shank relative to the column, while permitting rotation of the shank in the bore 97.

The yoke 99 includes a bar member 102 rigidly secured to the shank with spaced arms 103 and 104 extending forwardly of the bar member at the ends thereof. Each of the arms 103 and 104 has aligned apertures for receiving the shanks of bolts 105 or the like which also extend through ears 106 and 107 rigidly secured to the respective upright members 108 and 109 of a trackway 110, whereby said trackway is carried on the yoke 99 and is tilted laterally of the vehicle by rotation of the yoke 99 as later described.

The upright members 108 and 109 are channel-shaped and are connected at their upper ends by suitable plates or other structure to form a trackway cap 111. Cooperating with the cap member 111 to retain the upright members 108 and 109 in proper spaced relation and form a rigid structure are spaced connecting bars 112 and 113, the bar 112 preferably being substantially intermediate the height of the upright members and

the bar 113 adjacent the lower end of said trackway. Each of the bars 112 and 113 has end portions 114 secured as by welding to the outer surfaces of the webs of the upright members and the connecting portion 115 is spaced from the upright members to permit free movement of a hammer or impact member 116 which is slidably mounted in the channel-shaped upright members as illustrated in Fig. 3. The bar 112 also preferably has ears 117 extending rearwardly and downwardly therefrom for connection with an adjustable foldable brace 118 for tilting the trackway 110 fore and aft or longitudinally of the carriage or vehicle by moving said trackway about the axis of the bolts or pins 105.

The brace 118 consists of links 119 having one end pivoted on a pin 120 carried by the ears 117. The other ends of the links 119 are pivotally mounted on a pin 121 carried by an arm 122 intermediate the ends thereof. One end of the arm 122 is provided with an aperture 123 adapted to align with an aperture 124 in the links 119 when the links and arm are in alignment for receiving a bolt 125 for retaining the link and arms 119 in a stiff brace member. The links 119 are preferably provided with a stop 126 adapted to be engaged by the arm 122 when in alignment with the links 119 whereby the links and arms may be pivoted on the pin 121 in one direction only for folding the brace 118. The opposite end of the arm 122 has a threaded bore 127 adapted to receive a threaded shank 128 of an adjusting screw 129. The screw 129 is rotatably mounted and fixed against longitudinal movement in a bearing member 130, having trunnions 131 rotatably mounted in a bracket 132 fixed to the collar 101. The adjusting screw is provided with a crank member 133 to facilitate turning of the screw. With this arrangement, turning of the crank 133 screws the shank 128 into or out of the threaded bore 127 to lengthen or shorten the brace 118 and when the links 119 and arm 122 are held in alignment, as illustrated in Fig. 2, the turning of the crank 133 will tilt the trackway fore or aft of the carriage or vehicle.

When it is desired to position the trackway 110 as illustrated in Fig. 1, for transportation, the crank 133 is turned to tilt the trackway whereby the top thereof moves toward the rear of the vehicle. The bolt 125 is then removed from the apertures 123 and 124 whereby the links 119 and arm 122 may be relatively pivoted on the pin 121. The top of the trackway is then pulled over toward the rear of the vehicle to the position shown in Fig. 1, whereby said trackway engages and rests on a post member 134 fixed to the frame of the vehicle rearwardly of the seat 31. Suitable fastening devices may be applied for retaining the trackway in folded position during transportation.

When the trackway is in upright position as illustrated in Fig. 2, it may be tilted laterally of the vehicle by rotating the yoke 99 and shank 98 thereof in the bore 97. This tilting movement is controlled by means of a tubular member 135 rigidly fixed to the bar 102 of the yoke and depending therefrom. Slidably mounted in the lower end of the bore of the tubular member is a shaft 136 having a yoke 137 on the lower end thereof, the ears of which are trunnioned on a nut 138 threadedly mounted on a shank 139 which is rotatably mounted and fixed against endwise movement in ears 140 of a U-shaped bracket 141 suitably secured to the forward face of the column 88 whereby rotation of the threaded shaft

139 moves the nut 138 on said threaded shank thereby forcing the tubular member 135 from vertical position, tilting the yoke 99 and the trackway 110 carried thereby.

The hammer may be of any desired shape but is illustrated as having a substantially cylindrical portion 142 having laterally extending side flanges 143 and 144 adapted to slidably engage in the channels 145 and 146 respectively in the upright members 108 and 109 of the trackway 110. The lower face of the hammer is preferably concaved as at 147 to aid in driving posts without splintering the top of same and also to receive an adapter head 148 which is secured to the hammer by means of bolts 149. The adapter head is provided with an axial aperture for receiving the shanks of various tools on the hammer, such tools being a tamper with various extensions thereon, a paving patch removing tool, a chisel, a concrete baker, a cutter trim tool and various other tools for use in road or right-of-way repair and maintenance.

The hammer 116 is raised and lowered in the trackway under the control of the operator-driver at all times, however, it is preferable that the hammer raising and lowering mechanism be such as to permit substantially free dropping of the hammer. A cable 150 is attached to the upper end of the hammer 116 in any suitable manner with the upper end of said cable wound on a reel 151 rotatably mounted on a shaft 152 having ends mounted in suitable bearings 153 which are illustrated as being in walls of the housing 154 suitably mounted on the trackway cap 111.

The reel 151 is preferably operated hydraulically as illustrated in the diagrammatic hydraulic circuit, Fig. 7, which includes an hydraulic motor 155 having a shaft 156 on which is keyed a sprocket 157 having driving connection by a chain 158 with a sprocket 159 fixed to the shaft 152. A jaw clutch member 160 is keyed to the shaft 152 for rotation therewith and is also slidable thereon whereby the jaws of said jaw member are engageable with jaws 161 fixed to one end of the reel 151, the jaw member 160 being actuated by a yoke lever 162 which is operated by a single-acting, spring-loaded hydraulic cylinder 163 and piston 164. The cylinder and piston are arranged whereby when hydraulic pressure is applied to the cylinder 163, said pressure moves the piston 164 to compress a spring 165 to operate the lever 162 and move the jaw member 160 into engagement with the jaws 161. Release of pressure in the cylinder 163 allows the spring 165 to move the piston 164 to disengage the jaw member 160 from the jaws 161.

In the hydraulic circuit as illustrated, the prime mover 34 effects operation of the hydraulic pump 35 to draw fluid from a reservoir 166 and move said fluid through a conduit 167 to an actuating valve 168 of the plunger type and so constructed whereby the operation of the plunger 169 selectively directs fluid pressure to selected ends of the cylinder 83 to operate the piston therein to swing the A-frame laterally of the vehicle, but regardless of the position of the plunger 169, a portion of the hydraulic fluid passes through the valve 168 to a hammer control valve 170 which is also preferably of the plunger type. In neutral position of the plunger 171, the hydraulic fluid passes through the valve 170 to a conduit 172 to the reservoir 166. Operation of the plunger 171 moves same whereby the hydraulic fluid is directed through a conduit 173 which has a connection 174 with a conduit

175 leading to the cylinder 163 for application of fluid pressure thereto. The connection 174 also provides communication with a two-way relief valve 176 and a conduit 177 which communicates with the hydraulic motor 155, the discharge of the hydraulic motor passing through a return line 178 to the reservoir 166. Located in the line 178 is an auxiliary reservoir 179 to supply a storage of hydraulic fluid adjacent the discharge of the hydraulic motor.

In neutral position of the plunger 171, the opening to the conduit 173 is closed, thereby maintaining pressure in the conduit and cylinder 163 to retain the reel 151 and the hammer in selected position. In order to permit the hammer to drop, the plunger 171 is moved to provide communication of the conduit 173, through the valve 170 to the conduit 172 for flow of fluid from the conduit 173, thereby releasing pressure in the cylinder 163, permitting the spring 165 to force the piston 164 to move the jaw member 160 into disengaged position, allowing the reel 151 to spin freely on the shaft 152. If it is desired to stop the hammer in its downward movement, the plunger 171 is moved to hammer raising position, causing fluid pressure to be returned to the conduit 173 and apply fluid pressure to the cylinder 163 and piston 164 therein to effect engagement of the jaw member 160 with the jaws 161. This will drive the hydraulic motor 155 in the reverse to normal direction, pumping liquid from the reservoir 179 into the conduit 177, however, the valve 175 will prevent or limit flow of liquid therethrough whereby the fluid in the hydraulic motor will act as a brake and stop the fall of the hammer. With this arrangement, the valves 168 and 170 may be operated separately or simultaneously to move the A-frame laterally of the vehicle and to control operation of the hammer 116.

In operation of an apparatus constructed as described, and assuming same is in the position as shown in Fig. 1 for transportation, the vehicle is moved to the location of the work to be done. When at the proper site, force is applied to the upper end of the trackway to pivot it upwardly on the bolts or pins 105, moving the links 119 into alignment with the arm 122. When in alignment, the bolt 125 is inserted into the apertures 123 and 124 to retain the links and arm in alignment. By rotating the crank 133 to screw the shank 128 in the threaded bore 127, the trackways are tilted fore and aft as desired. By rotating the threaded shank 139, the nut 138 is moved thereon to move the tubular member 135 and tilt the yoke 99 whereby the trackway is moved to provide the proper side tilt or position relative to the vehicle. The desired tools may be applied to the lower end of the hammer for performing the work to be done. The prime mover 34 is then started to operate the pump 35 to provide the hydraulic fluid pressure to the valves 168 and 170. Then by manipulation of the valve lever to operate the valve plunger 171, fluid pressure is applied to the hydraulic motor 155 and to the hydraulic cylinder 163 whereby the piston 164 is moved to effect engagement of the jaw member 160 with the jaws 161 whereby the hydraulic motor rotates the reel 151 to wind the cable thereon and raise the hammer in the trackway. By moving the plunger 171 to hammer release position, the release of pressure allows the spring 165 to move the piston 164 to disengage the jaw member 160 from the jaws 161 to permit free rotation of the

reel 151 on the shaft 152 and substantially free dropping of the hammer 116. By repeating the manipulation of the valve 170, the hammer may be raised and dropped as desired.

Simultaneously the operator may operate the clutch 36 and gear shift lever 57 to effect forward or reverse movement of the vehicle and steer the vehicle whereby the effect of the drop of the hammer and the movement of the vehicle is to provide a progression of the work through a selected path. During this operation, the valve 168 may be manipulated to selectively operate the cylinder and piston 83 to move the A-frame 66 laterally of the vehicle and swing the trackway and thereby widen the path in which the work of the hammer is done. When the link 95 is connected to the bracket 96, the lateral movement of the A-frame 66 is such that the trackway stays parallel with the front axle 18 and the effect of the hammer is in a straight line parallel to said axle, but there is a limit in width to the path in which the hammer may be effective. By disconnecting the link 95 and securing the ear 93 to the bracket 94, the trackway is swung in an arc defined by the bolt 76, ball 64 and sleeve 62 whereby the total width of the path through which the hammer may be operated is extended.

A modified form of hammer raising and lowering mechanism is illustrated in Figs. 8 and 9, and includes a cylinder 180 mounted on the cap 111 transversely of the trackway 110. A piston 181 is slidably and sealingly arranged in the cylinder whereby application of fluid pressure between the piston and a closed end 182 of said cylinder moves the piston in the cylinder to extend a piston rod 183 fixed to said piston from the opposite end of the cylinder. Secured on the free end of the rod 183 is a head 184 having pivotal connections 185 and 186 with ends of links 187 and 188 respectively. Connected to the opposite ends of the respective links 187 and 188 are shafts 189 and 190, which extend through and are slideable in slots 191 and 192 of upper and lower plates 193 and 194 of a frame 195. The slots 191 and 192 preferably extend longitudinally of the vehicle and are rearwardly and forwardly of the trackway as illustrated in Fig. 9. Rotatably mounted on the respective shafts 189 and 190 are multiple sheaves 196 and 197. A cable 198 has one end connected to the hammer (not shown) and the other end extends upwardly and over a sheave 199 rotatably mounted in the cap 111 and then engages a sheave 200 rotatably mounted adjacent the plate 194 in the frame 195 and intermediate the multiple sheaves 196 and 197. The cable then extends around the multiple sheaves 197 and 196 to provide the desired mechanical advantage and extent of movement of the cable and hammer in response to bodily movement of the multiple sheaves 196 and 197. The end of the cable is secured to the framework 195.

The hydraulic circuit for operation of the raising and lowering mechanism includes the hydraulic pump 35, reservoir 166, conduit 167 and valves 201 and 202 which are substantially the same as the valves 168 and 170 respectively except that they are illustrated in a single unit. Operation of the valve 202 provides for flow of hydraulic fluid through a conduit 203 to the cylinder 180 to move the piston therein and the head 184 toward the frame 195. This movement causes the ends of the links connected to the shafts 189 and 190 to spread apart and thereby move the multiple

sheaves 196 and 197 apart, the movement of the sheaves being defined by the engagement of the shafts 189 and 190 with the slots 191 and 192. This movement draws upwardly on the cable 198 and raises the hammer, then operation of the valve 203 to a neutral position closes the port leading to the conduit 203 and holds the hammer in selected position. By moving the valve 202 to the dropping position, the conduit 203 is open for communication to a conduit 204 leading to the reservoir 165 whereby the weight of the hammer pulls on the cable 198 and moves the sheaves 196 and 197 toward each other forcing the piston 181 toward the closed end of the cylinder 180. The conduits 203 and 204 and the valve openings are relatively large for rapid flow of the hydraulic fluid to the reservoir and thereby the hammer has substantially free falling in the trackway, however, during the falling of the hammer the valve may be moved to neutral position closing the port to the conduit 203 to stop the fall of the hammer as desired. Also the rate of the drop of the hammer may be varied by only partially opening the port providing communication between the conduits 203 and 204.

It is believed obvious that I have provided a multi-purpose, hydraulically operated hammer and vehicle which is self-propelled in a structure that can be operated by one man and manipulated to provide smashing blows or light blows as desired on flat and sloping terrain, moved progressively forwardly and rearwardly and laterally or otherwise selectively operated to provide blows in selected locations for expediting work such as road and right-of-way maintenance and repair.

What I claim and desire to secure by Letters Patent is:

1. In apparatus mounting a portable drop hammer structure on a carriage having a transverse member, said drop hammer structure having a trackway, a hammer sliding in said trackway and mechanism raising said hammer and permitting substantially free falling thereof; a frame, means on the carriage pivotally and slidably mounting one end of the frame for sliding movement longitudinally of the carriage and swinging movement of the other end of said frame transversely of the carriage, rollers engaged with the transverse member and movable therealong, means pivotally mounted on the frame in spaced relation to said one end thereof for pivotal movement about a vertical axis and connected to the rollers for supporting the other end of the frame from said transverse member and guiding said other end of the frame in swinging movement transversely of the carriage, an upright column mounted on the frame at said other end thereof and rotatable about a substantially vertical axis, means mounting the trackway on the column, a source of fluid pressure, means selectively operated by said fluid pressure for swinging the frame laterally of the carriage, and means on the frame connected with the column for control of rotary movement of the column and independent lateral swinging movement of the trackway relative to the frame.
2. In apparatus mounting a portable drop hammer structure on a carriage having a transverse member, said drop hammer structure having a trackway, a hammer sliding in said trackway and mechanism raising said hammer and permitting substantially free falling thereof; a frame, means pivotally and slidably mounting one end of the frame on the carriage for slid-

11

ing movement longitudinally of the carriage, means on the frame adjacent the other end of same and having moving engagement with the transverse member of the carriage for supporting said other end of the frame and guiding said other end of the frame and guiding same in swinging movement laterally of the carriage, a column mounted on the frame and rotatable about a substantially vertical axis, means connecting the column to the frame for control of rotary movement of the column, means pivotally mounting the trackway on the column for swinging movement about an axis transversely of the carriage, adjustable brace means having one end pivotally connected with the column and the other end pivotally connected with the trackway above the pivotal mounting thereof for adjustably tilting the trackway fore and aft of the carriage, a source of fluid pressure, and means selectively operated by said fluid pressure for swinging the frame laterally of the carriage.

3. In apparatus mounting a portable drop hammer structure on a carriage having a transverse member, said drop hammer structure having a trackway, a hammer sliding in said trackway and mechanism raising said hammer and permitting substantially free falling thereof; a frame, means on the carriage pivotally and slidably mounting one end of the frame for sliding movement longitudinally of the carriage and swinging movement of the other end of said frame transversely of the carriage, rollers engaged with the transverse member and movable therealong, means pivotally mounted on the frame in spaced relation to said one end thereof for pivotal movement about a vertical axis and connected to the rollers for supporting the other end of the frame from said transverse member and guiding said other end of the frame in swinging movement transversely of the carriage, an upright column mounted on the frame at said other end thereof and rotatable about a substantially vertical axis, means pivotally mounting the trackway on the column for swinging movement about an axis transversely of the carriage, adjustable brace means having one end pivotally connected with the column and the other end pivotally connected with the trackway for adjustably tilting the trackway fore and aft of the carriage, a source of fluid pressure, means selectively operated by said fluid pressure for swinging of the frame laterally of the carriage, and means on the frame connected with the column for control of rotary movement of the column and independent lateral swinging movement of the trackway relative to the frame.

4. In apparatus mounting a portable drop hammer structure on a self-propelled carriage having front and rear axles, said drop hammer structure having a trackway, a hammer sliding in said trackway and mechanism raising said hammer and permitting substantially free falling thereof; a frame, means between the axles of the carriage pivotally and slidably mounting one end of the frame on the carriage, said end of the frame being slidable longitudinally of the carriage, means on the frame adjacent the other end of same and having moving engagement with the front axle of the carriage for supporting said other end of the frame therefrom and guiding same in swinging movement laterally of the carriage, a column mounted at said other end of the frame and rotatable about a substantially vertical axis, means connecting the column to the frame for control of rotary movement of the column, means pivotally mounting

12

the trackway on the column for swinging movement about axes transversely and longitudinally of the carriage, adjustable brace means having one end pivotally connected with the trackway above the pivotal mounting thereof and the other end pivotally connected with the column for adjustably tilting the trackway fore and aft of the carriage, means connected with the trackway pivotal mounting means and adjustably connected with the column for tilting the trackway laterally of the carriage, a source of fluid pressure, and means selectively operated by said fluid pressure for swinging the frame laterally of the carriage.

5. In apparatus mounting a portable drop hammer structure on a self-propelled carriage having front and rear axles, said drop hammer structure having a trackway, a hammer sliding in said trackway and mechanism raising said hammer and permitting substantially free falling thereof; a frame, means between the axles of the carriage pivotally and slidably mounting one end of the frame on the carriage for sliding movement longitudinally of the carriage and swinging movement of the other end of said frame transversely of the carriage, rollers engaged with one of the axles and movable therealong, means pivotally mounted on the frame in spaced relation to said one end thereof for pivotal movement about a vertical axis and connected to the rollers for supporting the other end of the frame from said one axle and guiding said other end of the frame in swinging movement transversely of the carriage, said other end of the frame extending beyond said one axle, an upright column mounted on the frame at said other end thereof and rotatable about a substantially vertical axis, yoke means pivotally mounted on the column for swinging movement about an axis longitudinally of the carriage, means pivotally mounting the trackway on the yoke means for swinging movement about an axis transversely of the carriage, adjustable brace means having one end pivotally connected with the trackway and the other end pivotally connected to the yoke means for adjustably tilting the trackway fore and aft of the carriage, adjustable means on the column and connected with the yoke means for tilting yoke means and the trackway thereon laterally of the carriage, a source of fluid pressure, means selectively operated by said fluid pressure for swinging the frame laterally of the carriage, and means on the frame connected with the column for control of rotary movement of the column and independent lateral swinging movement of the trackway relative to the frame.

6. In apparatus mounting a portable drop hammer structure on a carriage having a transverse member, said drop hammer structure having a trackway, a hammer sliding in said trackway and mechanism raising said hammer and permitting substantially free falling thereof; a frame, means on the carriage pivotally and slidably mounting one end of the frame for sliding movement longitudinally of the carriage and swinging movement of the other end of said frame transversely of the carriage, rollers engaged with the transverse member and movable therealong, means pivotally mounted on the frame in spaced relation to said one end thereof for pivotal movement about a vertical axis and connected to the rollers for supporting the other end of the frame from said transverse member and guiding said other end of the frame

in swinging movement transversely of the carriage, an upright column mounted on the frame at said other end thereof and rotatable about a substantially vertical axis, means mounting the trackway on the column, a source of fluid pressure, and means selectively operated by said fluid pressure for swinging the frame laterally of the carriage.

7. In apparatus mounting a portable drop hammer structure on a carriage having a transverse member, said drop hammer structure having a trackway, a hammer sliding in said trackway and mechanism raising said hammer and preventing substantially free falling thereof; a frame, means pivotally and slidably mounting one end of the frame on the carriage for sliding movement longitudinally of the carriage, means on the frame adjacent the other end of same and having moving engagement with the transverse member of the carriage for supporting said other end of the frame and guiding same in swinging movement laterally of the carriage, a column mounted on the frame and rotatable

about a substantially vertical axis, means connecting the column to the frame for control of rotary movement of the column, means pivotally mounting the trackway on the column for swinging movement about an axis transversely of the carriage, adjustable means on the column and connected with the pivotal mounting means of the trackway for tilting the trackway laterally of the carriage, a source of fluid pressure, and means selectively operated by said fluid pressure for swinging the frame laterally of the carriage.

EVAN E. DORKINS.
